UNITED STATES PATENT OFFICE.

DONALD S. BARROWS, OF ROCHESTER, NEW YORK.

DRAFT-RIGGING.

1,358,502.

Specification of Letters Patent

Patented Nov. 9, 1920.

Application filed May 31, 1918. Serial No. 237,487.

To all whom it may concern:

Be it known that I, DONALD S. BARROWS, a citizen of the United States, residing at Rochester, in the county of Monroe and 5 State of New York, have invented certain new and useful Improvements in Draft-Rigging; and I do hereby declare the following to be a full, clear, and exact description of the invention, such as will enable 10 others skilled in the art to which it appertains to make and use the same.

The invention relates to draft rigging for railway cars, and more particularly to a combined back stop and center sill tie casting which is primarily designed for application to the underframes of freight cars in which the center line of the draft rigging is below the center line of the center sills, and for use with that type of draft rigging in 20 which the coupler is movable rearwardly independently of the yoke in buffering and the buffering loads are transmitted to and carried by the back stop.

The principal object of my invention, 25 broadly stated, is to provide a combined back stop and tie casting for use under the conditions set forth above, which will possess the advantages of the well known and so-called bath tub type of back stop with 30 reference to the location of the rivet openings and ease of application to a car underframe, and which at the same time obviates the inherent defects of this old type of stop casting. To this end the main features of 35 the invention comprise a stop casting of hollow box form in which the buffering face is strengthened and reinforced by transversely disposed longitudinally extending webs or flanges which are adjacent the upper and 40 lower edges thereof and which face is further strengthened by means of a plurality of vertically extending flanges, the said longitudinally extending webs or flanges being provided with openings to permit access 45 to the continuous side walls of the said casting for the placing and driving of the attaching rivets.

Another feature of my invention is to provide a combined back stop and tie casting of 50 hollow box form which is approximately symmetrical through all central planes, thereby securing the greatest factor of strength with the least weight.

There are other features of my invention, 55 as will hereinafter more fully appear in connection with the detailed description of the

embodiment thereof which has been illustrated in the annexed drawings, in which,

Figure 1 is a top plan view of the invention as applied to a car, portions of the car 60 framing being shown in section.

Fig. 2 is a longitudinal vertical central section of the structure shown in Fig. 1.

Fig. 3 is a transverse vertical section taken on the line 3—3 of Fig. 1. 65

Fig. 4 is a front elevation of the combined back stop and tie casting, and

Figs. 5 and 6 are transverse vertical sections taken, respectively, on lines 5—5 and 6—6 of Fig. 1, looking in the direction indicated by the arrows. 70

Throughout the specification and drawings like parts are designated by like reference characters.

Although car underframes vary in height 75 with different types of cars, it is always necessary to maintain the draft riggings at a constant elevation above the rails on all cars so that the couplers thereof will interlock. To maintain this uniformity of height 80 it is necessary to locate the couplers and the attached draft riggings at different points with relation to the car center sills.

In cars in which it is necessary to locate the center line of the draft rigging below 85 the center line of the car sills, to maintain the couplers at the standard height it has heretofore been necessary to sacrifice strength, in the back-stop, for convenience of attachment. It is readily apparent to 90 those skilled in this art that a back-stop casting in the form of an I-beam section with the web thereof arranged in the line of draft and the flanges disposed equally above and below the web, is the strongest 95 type of casting for unit weight which can be devised. This construction, while highly desirable, cannot be used on cars of the type referred to for two reasons, first, the impossibility of driving the lower row of 100 rivets, that is the rivets below the web of the I-beam, and, second, because the distance from the web of the I-beam to the lower edge of the center sill does not give sufficient riveting area to afford a strong connection. 105

It has therefore been the practice in the past in cars of this construction to employ in place of the highly desirable I-beam section back stop, a back stop in the form of an open box having a bottom plate and vertical flanges extending upwardly from the edges of this bottom plate. This form of 110

2
back stop has been called the bath tub type. This back stop while permitting the necessary number of rivets to be employed to adequately attach the same to the car sills, 5 and not interfering with the driving of these rivets, is structurally weak, since the loads transmitted to the buffing face are out of line with the web and therefore exert a powerful leverage against the upper portion 10 of the striking face and distort the same.

The back stop hereinafter described is especially designed to overcome the defects pointed out in connection with the bath tub type in that the metal is arranged so as to 15 adequately reinforce the buffing face throughout its entire height and to distribute through the entire casting the loads transmitted to the buffing face.

In the drawings, the center sills are designated by the reference numerals 1, 1 between which is interposed the draft rigging 2. The draft rigging may be any of the well known types in which the cushioning mechanism and the coupler connecting 25 means is held from rearward movement by means of a centrally arranged back stop. The portion of the draft rigging illustrated comprises a yoke or coupler connecting means 3, a rear follower 4 which is interposed between the yoke 3 and the cushioning mechanism 5. The top cover plate is designated by the numeral 6. The rear face of the yoke 3 normally contacts the combined back stop and tie casting 7. This 30 tie casting, as illustrated, forms also a bolster center bearing, but it is to be understood that the invention is equally applicable to car construction in which the center bearing is separate from and located to the rear of the back stop member. The said casting 7 preferably comprises a plurality of upright webs or flanges 8, 9, 10 and 11, and a plurality of transversely extending webs or flanges 12 and 13.

45 A central portion of the web 8 is adapted to form the striking face of the said casting, that is, it is adapted to abut the rear face of one of the movable parts of the draft rigging. This face 8 may extend transversely from sill to sill or may be provided with offsets such as shown at 14, 14. The face 8 is connected to the vertical web 11 by the transversely disposed webs or flanges 12 and 13, and in order to brace and 50 strengthen the flange 12 I may provide the same with vertical ribs or flanges 15 and 16. The side walls or webs 10, 10 of the said casting preferably extend upwardly above the plane of the web or flange 12 and are 55 adapted to contact the adjacent sides of the center sills 1. Adjacent their lower ends these flanges 10 are provided with inwardly directed offsets 16^a so as to enable these webs to overlie the vertical flange 17 of the reinforcing angle iron 18. The flanges 10 are

also preferably extended to the rear of the face or flange 9 so as to provide additional riveting area.

For convenience, I may provide the casting 6 with laterally extending wings or projections 19 adjacent the offset portion 14 of the face 8. These projections 19 are preferably extensions of the lower flange 13 of the casting, and through these extensions and through the horizontal flanges of 75 the reinforcing angle bar 18, I may extend the rivets 20.

As will be clearly seen from Fig. 1, the flange 12 is provided on opposite sides of the thimble 21 with downwardly open slots or 80 recesses 22, 23, the lateral edges of the slot 22 being reinforced by the flanges 16 herefore referred to. The lower flange 13 of the stop casting may be provided with a plurality of openings 24 which are preferably positioned substantially as shown in the drawings. The openings 22 and 23 permit the withdrawal of the cores after the casting process and also provide means whereby the lower row of rivets 25 may be 90 inserted and driven after the casting is placed in position on the car underframe.

From the foregoing description it will be seen that the buffing face 8 is braced and strengthened adjacent its upper and lower edges by means of the transversely disposed longitudinally extending webs or flanges 12 and 13, and that the flange 12 is further reinforced by means of the downward extending ribs 15 and 16, these ribs being practically continuous from the face 8 to the transversely disposed vertically extending rib or flange 11. The lower flange 13 is also reinforced by a transversely extending rib 26 which is preferably placed in alinement 100 with the offset portions of the wall 8. It will also be obvious that the side webs 10 are maintained against deformation by the webs 8, 9 and 11, the latter web being preferably extended upwardly above the plane of the flange 12 so as to reinforce the correspondingly extended portions of the side walls 10. 105

Having now fully described my invention, although it is to be understood that by the foregoing description I do not intend to limit myself to the exact details, since the terms used are to be understood in their descriptive and not in their limiting sense, what I claim and desire to secure by Letters Patent is:

1. In a draft rigging, the combination with the center sills, of a combined back stop and tie casting adapted to abut a movable element of the draft rigging, said casting being provided with a continuous buffing 125 face and a pair of side walls, and means for connecting the upper portions of the said side walls to said buffing face, said means involving a transversely extending web, said web having an opening therein and upright 130

flanges formed on the side edges of the said opening.

2. In a draft rigging, the combination with the center sills of a casting adapted 5 to form a stop for a movable element of the draft rigging and a tie member for the said sills, said casting comprising a pair of end walls, a pair of side walls and a pair of transversely extending webs or flanges, 10 said webs serving to operatively connect, respectively, the upper and lower portions of said end walls to the said side walls, one of said webs being provided with a plurality of upright flanges, said flanges being spaced 15 from the other of the said webs.

3. In a draft rigging, the combination with a pair of center sills, of a combined stop and tie casting adapted to be connected to the adjacent faces of the said sills 20 and to abut a movable element of the draft rigging, said casting having a pair of upright transversely extending end walls one of which is adapted to form a striking face, 25 a pair of upright side walls each connected to the said end walls and means for further

connecting one of the said end walls to the said side walls, said means comprising a horizontally disposed transversely extending perforated web, provided with downwardly directing flanges.

4. In a draft rigging, the combination with a pair of center sills, of a combined back stop and tie casting of hollow box form, said casting having the side walls thereof connected to the adjacent faces of 35 the said sills and its forward face adapted to abut a movable element of the said draft rigging, said casting having transversely disposed top and bottom members adapted to connect the side walls to the forward 40 face, one of which is provided with an opening and means for reinforcing said last named member, said means comprising a flange depending from the side edges of the 45 said opening and a plurality of webs connecting said flange to the forward face of the said casting.

In testimony whereof I affix my signature.

DONALD S. BARROWS.
